PROPELLER BLADE CONSTRUCTION

Erle Martin, West Hartford, Conn., assignor to
United Aircraft Corporation, East Hartford,
Conn., a corporation of Delaware

Application April 22, 1944, Serial No. 532,246

3 Claims. (Cl. 170—159)

1

This application is a continuation-in-part of U. S. application Serial No. 416,058, filed October 22, 1941 (now abandoned) by Erle Martin for Propeller blade constructions.

This invention relates to improvements in aeronautical propellers and has particular reference to an improved form of metal blade for such a propeller.

An object of the invention resides in the provision of an improved aeronautical propeller having metal blades which will not be materially weakened by the scratches and abrasions to which the faces of such blades are subject in operation.

A further object resides in the provision of an improved aeronautical propeller having metal blades which are initially curved to relieve destructive stresses in certain portions of the blade during propeller operation.

Other objects and advantages will be more particularly pointed out hereinafter or will become apparent as the description proceeds.

In the accompanying drawing in which like reference numerals are utilized to designate similar parts throughout, there is shown a suitable mechanical arrangement for the purpose of disclosing the invention. The drawing, however, is for the purpose of illustration only and is not to be taken as limiting the invention since it will be apparent to those skilled in the art that various changes in the illustrated construction may be resorted to without in any way exceeding the scope of the invention.

In the drawing,

Fig. 1 is a diagrammatic side elevation of a propeller, the initial deformity of the blades being somewhat exaggerated for the sake of clearness in the illustration.

Fig. 2 is a diagrammatic front elevation of the propeller of Fig. 1.

Fig. 3 is a transverse sectional view on the line 3—3 of Fig. 1 looking in the direction of the arrows.

Fig. 4 is a Goodman diagram illustrating the difference in vibratory stress carrying ability of surfaces under different amounts of tension and compression.

The two sides of a propeller blade are called the thrust face and the camber face or side. The thrust face, which is located on the rearward side of the blade relative to the direction of travel of the aircraft on which the propeller is mounted, is the face which comes in contact with solid particles in the air. These particles such as pieces of stone or cinders picked up from the runways cause scratches or nicks in the thrust face. This abrasion in the form of scratches or nicks greatly reduces the fatigue strength of the propeller blade particularly when the nicked portion is in tension. I have discovered, however, that if the abraded surface is maintained under

stress which is not eccentric with respect to the camber surface, the fatigue strength of the abraded surface is not reduced to the same extent as where the surface is maintained under tension. A blade designed so that the surface subject to abrasion is always under compression during operation, could, therefore, be depended upon to carry higher stresses or a smaller amount of blade material could be used than in a blade designed to have the abraded surface under tension.

2 In order to accomplish the object of maintaining the thrust face under a steady compression, the propeller blades are curved away from and substantially normal to the thrust face 25, as shown in Figs. 1 and 2. This gives a blade which curves forward with respect to the direction of travel of the aircraft on which the propeller is mounted and backward with respect to the direction of rotation of the propeller. The metal propeller blades, which are indicated by the numerals 22 and 24, are secured to a hub 16 mounted on a drive shaft 18, projecting from a propeller driving engine 20. Centrifugal force will tend to straighten blades curved as shown in Figs. 1 and 2, thus placing the camber surfaces 23 under increased tension and the thrust faces 25 under compression.

3 The relation between the fatigue strength of members under tension and members under compression is clearly illustrated in the Goodman diagram, Fig. 5. In this diagram the vertical lines to the right of line 10 and numbered 1 to 7 indicate the steady tension load in a blade. The horizontal lines above the line 12 and extending to the right of line 10 and numbered 1 to 1 also indicate tension in the blade. This diagram is read by moving to the right along the line 12 to a point which represents the steady tension in the blade, then traveling upwards from that point to the intersection with lines C, C of the diagram.

4 The points represented by these intersections are the safe limits of the vibratory stress of an abraded surface under the selected steady load. Thus, selecting 10,000 lbs. per sq. in., represented by numeral 1, as the steady load, it is found that this line intersects the lines C, C at about 1,000 and 19,000 lbs. per sq. in. so that the safe vibratory stress, as indicated by the line A, would be between 1,000 and 19,000 lbs. per sq. in. or a total range of 18,000 lbs. per sq. in. Another way of explaining the relation would be to consider that the steady load of 10,000 lbs. per sq. in. has superimposed upon it a varying load of plus 9,000 lbs. per sq. in. and minus 9,000 lbs. per sq. in. giving final resultant loads of 1,000 lbs. per sq. in. and 19,000 lbs. per sq. in. as the safe limits of vibratory stress. It will be noticed that as the steady tension is increased, the safe notched fatigue range decreases.

5 The intersection of the vertical lines with the lines D, D of the diagram indicate the safe limit

of vibratory stress for an unbraded blade which is much greater than the safe stress for an abraded blade under the same steady tension.

The portion of the diagram to the left of line 10 and below line 12 shows the safe vibratory stresses that may be imposed upon a surface which is under compression. It will be noticed that the safe notched stress increases for surfaces under compression until it equals the safe stress for unnotched surfaces. Taking a point represented by the line B at which we would have a steady compression of approximately 15,000 lbs. per sq. in., we find that the lines C, C and D, D have merged into a single line and that the safe notched fatigue range is between approximately 3,000 lbs. per sq. in. tension and 33,000 lbs. per sq. in. compression, giving a safe range of approximately 36,000 lbs. per sq. in. as contrasted with the 18,000 lbs. per sq. in. permissible when the blade had but 10,000 lbs. tension. This represents a tremendous increase in blade strength as it doubles the permissible vibratory stress level on the blade.

It has been standard practice to shape propeller blades so that the centers of gravity of the various transverse sections of the blade lie on a substantially straight line extending lengthwise of the blade and referred to as the major axis of the blade. The centrifugal force in such a blade incident to propeller operation acts in a direction tending to move these centers of gravity outwardly along their common axis and thus tends to stretch the blades substantially uniformly putting all of the blade surface in a condition of tension.

Thrust forces acting on a blade tend to bend the blade forward and place the thrust face in tension. In a blade in which the centers of gravity of the transverse sections lie on a substantially straight line extending lengthwise of the blade, this action places the thrust face in greater tension than the camber face because the thrust-induced load adds to the centrifugally-induced load on the thrust face. It has been proposed to initially bend the blades forward so that centrifugal force in acting on the blades and tending to straighten them would substantially balance the thrust-induced stresses and thus reduce the tension in the thrust face. The two faces of the propeller will then have substantially the same tension, thus reducing the highest stress on the blade and equalizing the stresses in the two faces of the blade. I propose to curve the propeller blade an amount greater than that necessary to equalize the stresses acting on the blade and indeed to curve it to such an extent that stresses induced by the action of centrifugal force create a compression stress in the thrust face of the blade greater than the centrifugally induced tension stress so that the thrust face of the blade is placed under a steady compression stress at all speeds for which the propeller is designed.

Another way of explaining this invention would be to consider that we have a normal blade with a substantially equal centrifugally induced tension stress on each of the faces and for purposes of illustration let us call that stress 5,000 lbs. per sq. in. tension. We now curve the blade forwardly so that centrifugal force in straightening the blade will decrease the resultant tension stress on the thrust face by 15,000 lbs. per sq. in., giving approximately 10,000 lbs. per sq. in. steady compression. This same action will increase the tension stress on the camber face by approximately the same amount so that we would have

a tension force of approximately 20,000 lbs. per sq. in. tension on the camber face.

Referring now to our Goodman diagram, we find that the notched fatigue range for 10,000 lbs. per sq. in. compression is about 36,000 lbs. per sq. in., that is, 18,000 lbs. per sq. in. plus and 18,000 lbs. per sq. in. minus and that the unnotched fatigue range for 20,000 lbs. per sq. in. tension is approximately 34,000 lbs. per sq. in., that is, 17,000 lbs. per sq. in. plus and 17,000 lbs. per sq. in. minus. By thus designing a blade so that considering the thrust face as a notched surface and the camber face as an unnotched surface, we have a fatigue range of approximately the same amount for both surfaces, we can greatly increase the permissible safe vibratory stress. In the example chosen above, it will be noted that for 5,000 lbs. per sq. in. tension, we have a notched fatigue range of a little less than 20,000 lbs. per sq. in. and this would be the determining factor. However, by bending the blade forward so that the steady compression stress in the thrust face is 10,000 lbs. per sq. in. and the steady tension stress in the camber face is 20,000 lbs. per sq. in., we have increased the permissible vibratory range from 20,000 lbs. to about 34,000 lbs. per sq. in. This same phenomenon is apparent when both sides of the blade are in tension as, for instance, starting with 30,000 lbs. per sq. in. as the steady tension stress, we find we have a permissible notched range of about 12,000 lbs. per sq. in. If now that steady tension stress of 30,000 lbs. per sq. in. is reduced by 15,000 lbs. per sq. in. on the thrust side and increased 15,000 lbs. per sq. in. on the camber side, we find that we have increased the permissible fatigue range on the thrust side from about 12,000 lbs. per sq. in. to approximately 15,000 lbs. per sq. in. and on the camber side to about 15,000 lbs. per sq. in. It is at once apparent, however, that while some advantages may be obtained even when the thrust face remains in tension, these advantages are materially greater when the thrust face is maintained under a steady compression load.

The shape of a blade, in which the thrust face is maintained under a steady compression load under all operating conditions, could be determined by the following formula:

$$\int_X^R F_c \frac{dy_0}{dx} dx = \int_X^R tdx - \int_X^R F_c \int_0^X \frac{M}{EI} dx dx - M$$

in which:

I =minor moment of inertia of section at radius X
 A =area of section at radius X

C =distance from neutral axis to outermost fibre on face side at radius X

t =total blade air load per in. of radius at maximum operating power and thrust conditions for radius X

F_c =centrifugal stress at station

$$X = \frac{1}{A} \int_X^R \frac{R}{X} \gamma \omega^2 A dx$$

S =desired face side stress at station X

M =desired bending moment

$$\left(\frac{F_c}{A} - s \right) \frac{I}{C} \text{ at station } X$$

E =modulus of elasticity

Y_0 =desired offset at any station X

ω =rotative speed radians per/sec.

x =radius of section being considered

R =radius of blade tip

γ =mass density of blade material

This formula is solved for Y_0 for any given value of X . The Y_0 points obtained would deter-

mine the locus of the centers of gravity of the various blade sections. In solving this formula S is given a value which is the steady compressive stress selected as the desirable quantity to be maintained in the thrust face at operating conditions.

This formula is based on conditions existing when the blade is at substantially O pitch and the curvature is, therefore, substantially all in a direction parallel to the axis of rotation of the propeller and there is substantially no curvature in the direction of the plane of rotation of the propeller. While the conditions which exist when the propeller pitch is changed to a value used in normal operations will differ from the conditions which exist at O pitch, the change in forces acting on the blade and tending to produce tension or compression in the faces thereof are such that their effect is substantially balanced and the resultant effect on the blade is substantially that determined by the above-identified formula. Hence, a blade curved to an extent at least as great as the line determined by solution of the above formula will have its thrust face maintained under the selected desired stress during selected operating conditions.

It is to be understood that the invention is not limited to the specific embodiment herein illustrated and described, but may be used in other ways without departure from its spirit as defined by the following claims.

I claim:

1. An aeronautical propeller having a hub and metal blades extending substantially radially outward from said hub, said blades having a thrust face and being initially curved away from said face to an extent at least as great as the extent determined by the formula

$$\int_X^R F_c \frac{dy_0}{dx} dx = \int_X^R t dx \int_X^R F_c \frac{X M}{EI} dx dx - M$$

I =minor moment of inertia of section at radius X
 A =area of section at radius X

C =distance from neutral axis to outermost fibre on face side at radius X
 t =total blade air load per in. of radius at maximum operating power and thrust conditions for radius X

F_c =centrifugal stress at station

$$X = \frac{1}{A} \int_X^R \frac{R}{X} \gamma \omega^2 Adx$$

S =desired face side compressive stress at station X

M =desired bending moment=

$$\left(\frac{F_c}{A} - s \right) \frac{I}{C} \text{ at station } X$$

E =modulus of elasticity

γ =desired offset at any station X

ω =rotative speed radians per/sec.

x =radius of section being considered

R =radius of blade tip

γ =mass density of blade material

2. A metal propeller blade having a longitudinally extending concave forward surface and a longitudinally extending convex rear face surface and having the centers of gravity of its various transverse sections located on a line which curves in a direction away from said rear face surface as it extends from the shank to the tip portion of the blade, said blade adapted to be mounted in a blade supporting hub so as to extend substantially radially from said hub adjacent the hub with the outer portion of the blade curved forward to an extent that, as a result of the action of centrifugal force on the blade, tending to straighten the blade and force it into a radial position during operation of the propeller in the operating speed range, the predominant stress acting on the rear face surface of the blade is a compressive stress, said forward curvature being limited so that the tensile stress in the front face of the blade is within the allowable working stress of the blade material when the propeller is operated within said speed range.

3. An aeronautical propeller having an operating speed range and having a hub and metal blades extending substantially radially outward from said hub, each blade having a thrust face and being initially curved away from said face to render the same convex, thus providing a blade curved axially forwardly and curved rearwardly with respect to the direction of rotation, said curvature being greater than the amount necessary to neutralize, by the effects of centrifugal force, the thrust induced bending forces acting on said blade when operating in said speed range, said curvature being such that said blades are substantially straightened by centrifugal force acting on said blade during operation within said range, said straightening producing a compressive stress in said thrust face of said blade greater than the tension stresses induced in said face, during operation within said range, by thrust forces and centrifugal forces, and said curvature being less than the amount at which the tensile stress in the opposite face of the blade, when operating within speed range, would exceed the allowable working stress of the blade material.
